United States Patent Office

Des. 226,480
Patented Mar. 13, 1973

226,480

GUNSIGHT

Richard Mauro, 2326 Powell Ave.,
Bronx, N.Y. 10462

Filed May 23, 1972, Ser. No. 256,208

Term of patent 14 years

Int. Cl. D22—01

U.S. Cl. D22—8

FIG. 1

FIG. 2

FIG. 3

FIG. 4

FIG. 1 is a perspective view of a gunsight showing my new design;

FIG. 2 is a left side elevation of FIG. 1;

FIG. 3 is a front elevation of FIG. 1; and

FIG. 4 is a rear elevation of FIG. 1.

I claim:

The ornamental design for a gunsight, as shown.
